CABINET LOCK

Solomon Wise, Shaker Heights, Ohio

Application January 30, 1950, Serial No. 7,572

Term of patent 14 years

(Cl. D50—7)

To all whom it may concern:

Be it known that I, Solomon Wise, a citizen of the United States, residing at Shaker Heights, in the county of Cuyahoga, State of Ohio, have invented a new, original, and ornamental Design for a Cabinet Lock, of which the following is a specification, reference being had to the accompanying drawing, forming a part hereof, in which:

Fig. 1 is an elevational view of one side of a cabinet lock showing my new design;

Fig. 2 is an elevational view of the lock from the side opposite to that of Fig. 1;

Fig. 3 is a plan view of the lock taken from the top as viewed in Fig. 1;

Fig. 4 is an elevational view from the left end of Fig. 1;

Fig. 5 is a perspective view showing the lock in place on the door handle of a refrigerator cabinet, the dominant features of the design being shown in solid lines.

I claim:

The ornamental design for a cabinet lock, as shown and described.

SOLOMON WISE.
